BRUSH CUTTER

Frank Broemme, Palmyra, and Paul Puder,
Riverton, N. J.

Application May 14, 1934, Serial No. 725,524

7 Claims. (Cl. 30—11)

Our invention relates to a new and useful cutter and it relates more particularly to a cutter especially well adapted for cutting brush and other under-growth in inaccessible places, our 5 novel cutter being provided with means for holding the twig or branch to be cut while such twig is being severed, thus rendering our novel cutter operable with one hand automatically and without any attention on the part of the operator.

10 In the accompanying drawing:

Fig. 1 represents a front end elevation of the cutter embodying our invention.

Fig. 2 represents a side elevation of Fig. 1 showing the cutter in its inoperative position.

15 Fig. 3 represents a fragmentary view partly in section and partly in elevation taken on line 3—3 of Fig. 1 and showing details of construction.

Fig. 4 represents a view similar to Fig. 3 showing the device in the process of cutting a twig.

20 Fig. 5 represents a fragmentary section on line 5—5 of Fig. 2.

Fig. 6 represents a section on line 6—6 of Fig. 2.

25 Referring to the drawing, our novel cutter comprises a stem or shank 1 which may be of any desired length depending upon the use to which the device is to be put, said stem being preferably formed of two channel members 2 and 3 positioned back to back and suitably secured in spaced relation to each other, as best seen in Fig. 6. The stem 1 is provided with any suitable handle 4 and is preferably deflected as at 5 to facilitate operation and to facilitate access to the brush to be 30 cut. The other end of the stem 1 terminates in a substantially straight portion 7 which forms a guide for the mounting and operation of the holding and cutting blades next to be described. The channel 2 is engaged by the slide 8 which car-

35 ries the blade supporting member 9. The blade supporting member 9 either has integrally formed therewith or rigidly carries the blade 10 which projects at an angle to the guide 7, as best seen in Figs. 2, 3 and 4. The blade 10, except for sliding longitudinally of the guide 7, is otherwise fixed. The blade supporting member 9 is engaged by one end of the spring 11, the other end of which is anchored at 12 to the stem or shank 1. 40 13 designates a stop for limiting the movement 45 of the blade 10 in a direction away from the handle 4, the blade 10 and its supporting member 9 being pulled towards the handle 4 when the pull on the device ceases. 15 designates a second blade which is pivoted at 16 to the supporting member 9 which carries the blade 10, the blade 15

being normally in the position shown in solid lines in Figs. 2 and 3 in an out-of-the-way or inoperative position. In this position the blade 15 is prevented from further movement in the direction of the arrow in Fig. 3 by resting against the yielding stop 17. The outer end of the blade 15 is curved, as at 19, to produce a cam effect which is adapted to cooperate with the cam element 20 positioned in the outer end of the guide 7. The movement of the blade 19 and the blade supporting member 9 towards the handle 4 is limited by the stop 21.

5 The operation is as follows: When it is desired to cut a twig 22, the device is held by the handle 4 and the front guide portion 7 thereof is inserted until the twig 22 rests against the recess 23 in the blade 10. The operator then pulls on the handle so that the blade 10, together with the supporting member 9, slides within the guide 7 against the tension of the spring 11. As 10 the blade 10 and the supporting member 9 slide towards the outer end of the guide 7 the rounded edge 19 of the blade 15 rides over the cam 20, thus forcing the blade 15 to project outwardly 15 towards the blade 10, as shown in Fig. 4. In this position the twig 22 is held fast in the recess 23 between the blades 10 and 15. Further pull on the handle 4 will exert further pressure on the blades 10 and 15 and thus severs the twig 22 20 whereupon the blades 10 and 15 will assume the position shown in dotted lines in Fig. 2. Immediately after this position is reached the spring 11 pulls the blade 10 away from the position shown in dotted lines to the position shown in solid lines in Fig. 2, and the yielding stop 17 acting on the rear outer end of the blade 15 serves to push it back into its inoperative position, as shown in Figs. 2 and 3. The device is now again ready for use.

25 It will be seen from the description of the parts and the explanation of the operation that by merely holding the cutter by the handle 4 with one hand the operator is able to extend the cutter into any out-of-the-way place which would otherwise be inaccessible to pruning shears or other 30 devices necessitating the use of both hands in their operation. It will further be seen that the cutting action is effected by merely pulling on the handle, and since it is obvious that the average person can exert more force by pulling 35 than by attempting to operate shears with both hands away from the body it will be seen that our novel cutter is much more efficient, in that it enables the cutting of relatively thick brush, 40 twigs or branches, with the greatest ease. It 45

will be noted that the portion of the guide 7 which extends beyond the blade 10 is reduced to a minimum so as to constitute minimum obstruction in the manipulation of the device. The deflection of the shank 1 at 5, or in any other desired direction or to any other desired extent, renders it possible to operate the device successfully at points not in line with the direction of the hand of the operator. It will further be seen that the device can be made at a very low cost, due to its simplicity and the small number of parts and that the blades 10 and 15 are easily available for sharpening without removal from the guide 7, although the removal of the blades from the guide 7 involves very little time or effort.

We claim:

1. A cutter of the character stated, comprising a shank, one end of which serves as a handle, a rigidly mounted blade longitudinally slidable at the other end of said shank, a second blade having pivotal relation to and slidable with said first mentioned blade and a cam near the end of said shank for actuating said second blade into cutting relation with said first blade.
2. A cutter of the character stated, comprising a shank, one end of which serves as a handle, a rigidly mounted blade longitudinally slidable at the other end of said shank, a second blade having pivotal relation to and slidable with said first mentioned blade, a cam near the end of said shank for actuating said second blade into cutting relation with respect to said first blade and means for limiting the sliding movement of said blades.
3. A cutter of the character stated, comprising a shank, one end of which serves as a handle, a rigidly mounted blade longitudinally slidable at the other end of said shank, a second blade having pivotal relation to and slidable with said first mentioned blade, a cam near the end of said shank for actuating said second blade into cutting relation with respect to said first blade and means for actuating said second blade.
4. A cutter of the character stated, comprising a shank, one end of which serves as a handle, a rigidly mounted blade longitudinally slidable at the other end of said shank, a second blade

having pivotal relation to and slidable with said first mentioned blade, means for actuating said second blade, comprising a cam-shaped formation on the outer end of said second blade and a cam near the end of said shank whereby said second blade is actuated into cutting relation with respect to said first blade and tensioning means for normally retaining said second blade in an inoperative position.

5. A cutter of the character stated, comprising a shank, one end of which serves as a handle, a rigidly mounted blade longitudinally slidable at the other end of said shank, a cam near the end of said shank for actuating said second blade into cutting relation with respect to said first blade 10 and a second blade having pivotal relation to and slidable with said first mentioned blade, the end of said shank which carries said blades being offset with respect to the other end thereof.

6. A cutter of the character stated, comprising a shank, one end of which is adapted to serve as a handle, a rigidly mounted blade slidable longitudinally of the other end of said shank and permanently extending at an angle thereto, a second blade having pivotal relation to and slidable with 25 said first blade, means for normally retaining said second blade in an inoperative position, and a cam near the end of said shank for actuating said second blade from said inoperative position to retaining and cutting position with respect to said 30 first blade.

7. A cutter of the character stated, comprising a shank, one end of which is adapted to serve as a handle, a rigidly mounted blade slidable longitudinally of the other end of said shank and 35 permanently extending at an angle thereto, a second blade having pivotal relation to and slid able with said first blade, means for normally retaining said second blade in an inoperative position, a cam near the end of said shank for actuating said second blade from said inoperative position to retaining and cutting position with 40 respect to said first blade, and means for limiting the sliding movement of said blades.
